(57) CLAIM

The ornamental design for a decorative table lamp, as shown and described.

DESCRIPTION

FIG. 1 is a perspective view of a decorative table lamp illustrating our new design;

FIG. 2 is a top view thereof;

FIG. 3 is a bottom view thereof;

FIG. 4 is a front view thereof; and,

FIG. 5 is a side view thereof.

The gear teeth are shown fragmentarily in FIGS. 2 and 3 for convenience of illustration.

The broken lines shown are for illustrative purposes only and form no part of the claimed design.
